UNITED STATES PATENT OFFICE.

FRITZ P. MANSBENDEL, OF BROOKLYN, NEW YORK.

MOTOR.

Original application filed November 3, 1916, Serial No. 129,406. Divided and this application filed October 11, 1921. Serial No. 507,127.

This invention relates to a novel form of mechanical movement whereby an oscillatory motion may be converted into a continuous rotary motion, and more particularly to its embodiment in a motor device through a plurality of driving members operative on a common shaft; and this application for patent is a division of my prior application Serial Number 129,406, filed November 3rd, 1916.

It has for its object means whereby a comparatively slow rotation may be directly effected as a substantially continuous movement and without the use of intermediate gearing if desired. Such mechanism being demanded largely, for example, in connection with advertising devices.

A still further and more specific object of the present invention is a motor of the character specified wherein the transmission bands are attached to opposite ends of an oscillatory driving member so that while one band is recovering from the power stroke the other band begins its power stroke cycle.

Other and further objects of the present invention will in part be obvious and will in part be pointed out hereinafter by reference to the accompanying drawings wherein like parts are represented by like characters throughout the several figures thereof.

Realizing that the present invention may be embodied in constructions other than those specifically herein shown I desire that the disclosure herewith shall be considered as illustrative and not in the limiting sense.

Figure 1 is a plan view illustrating more or less diagrammatically one form of the present invention.

Figure 2 is a side elevation of the device shown in Figure 1 and illustrating a portion of the support broken away;

Figure 3 is an end elevation of the device illustrated in Figure 2.

Heretofore in the art of oscillating motors it has been customary to provide a member with a single transmission band and in view of the fact that the power stroke of the band appears to be restricted to the stroke of the operating member which is away from the axis of the rotating wheel or drum, it appears that the driving member is only effective during one-half of its movement, sub-

stantially similar to the operation of a single acting steam engine.

The present invention is designed more especially to utilize the complete cycle of the oscillation of the driving member as power strokes and to this end the parts are constructed so that both movements of the oscillatory driving device are effective as power strokes. This may be accomplished in various ways and one simple way comprises pivoting the driving member in such manner that it oscillates upon the pivot and the connecting transmission bands on opposite sides of the axis of the pivot so that when one band is tensioned the other band is released and vice versa. These bands are then brought into engagement with a suitable drum or drums mounted upon a driving shaft so that the energy from the bands may be transmitted directly to the shaft.

Referring now more especially to the drawings, and to Figures 1 and 2, in which a plurality of wheels 1 are indicated, the same are mounted on a common shaft 2 and provided with respective circumferential grooves 3 with flexible cords or bands 4 occupying a portion of the circumference of the said wheels. One end of each of these cords is connected to a spring 5 while the other ends of the cords are connected to opposite arms of an armature 6 which is fulcrumed between said points of connection. This armature 6 is adapted to be rocked by electromagnets 7 and 8 that are adapted to be energized by a commercial alternating current or the like. This may be conveniently effected by polarizing such magnets; that is to say, maintaining the pole pieces thereof of the same polarity and employing a commercial alternating current from a suitable source of supply such as 9, Figure 1, to energize the same. This causes the armature to be oscillated at a high rate of speed, and in quick short strokes which impart a plurality of impulses to the bands 4 and thereby applies a large number of power strokes to each rotation of the shaft 2.

When the armature 6 oscillates in one period of movement due to a suitable current in the magnet, a pull is exerted on one band 4 while the other band is slack, and during the oscillation in the other direction

or period the condition in the bands is reversed, thus while one band is slackening the other is tightening so that a substantially continuous torque is maintained on the 5 shaft 2 through the wheels 1.

Having thus described my invention, what I claim is:

1. A motor of the character specified comprising in combination a plurality of 10 rotatable disks, a common driving shaft upon which said rotatable disks are rigidly mounted, a vibrating member pivoted in such manner that a portion of each end of said member extends beyond the pivot and 15 over one of the disks, transmission means operatively connected to said vibrating member and encircling a portion of each disk, an actuator to vibrate said vibrating member in quick short strokes, in such manner that said means in connection with one 20 end of the member is relaxed when the means in connection with the other end of said member is taut to alternately impart rotary motion to said disks whereby said shaft is rotated continuously in one direction.

2. A motor of the character specified, comprising in combination a driving shaft, 30 a plurality of driving pulleys fixedly mounted to the driving shaft, a vibrating member pivoted in substantially the middle thereof, with the pivot located between certain of said driving pulleys so that when 35 said member is vibrated the ends thereof alternately move toward and away from certain of said pulleys, a plurality of flexible transmission means secured to said member and encircling a portion of certain 40 of said pulleys, and means for vibrating said member in quick short strokes, in such manner that said flexible transmission means are alternately effective upon certain

of said pulleys to drive said shaft continuously in one direction.

3. A motor of the character specified 45 comprising in combination a driving disk, a flexible transmission member encircling a portion of said driving disk, vibrating means connected to one end of said transmission member, the pivot for said vibrating means being eccentric to the axis of the driving disk and at substantially right angles to the axis of rotation of said disk, in such manner that the movement of said vibrating means is an arcuate movement 50 which intersects the normal straight line pull of said transmission member, means for vibrating said vibrating means at a high rate of speed and in short quick strokes, and tensioning devices to maintain said transmission member normally in engagement 55 with said disk.

4. A motor of the character specified comprising in combination a plurality of 60 rotatable disks, a common driving shaft 65 upon which said rotatable disks are rigidly mounted, a vibrating member pivoted between the disks in such manner that one end of said member extends outwardly beyond one of the disks and the other end 70 extends in the opposite direction beyond the other disk, a transmission band operatively connected to each end of said vibrating member with each band encircling a portion of the adjacent disk, an actuator to 75 vibrate said vibrating member in quick short strokes, in such manner that the band connected with one end of the member is relaxed when the band connected with the other end of said member is taut to alternately impart rotary motion to said disks 80 whereby said shaft is rotated continuously in one direction.

FRITZ P. MANSBENDEL.
